GRAVE COVER

Purvis T. Hamm, New Braunfels, Tex.

Application August 13, 1940, Serial No. 352,463

1 Claim. (Cl. 27—30)

This invention relates to a grave cover and it consists in the constructions, arrangements and combinations herein described and claimed.

It is the cardinal purpose of the invention to provide a grave cover which will effectively protect the grave against weed growth, as well as prevent sinking of the grave, and in addition function as an attractive marker for the grave.

It is also an object of the invention to provide a grave cover of economical construction, and one which is adjustable to different grave lengths.

Additional objects, advantages and features of invention will be apparent from the following description considered in conjunction with the accompanying drawing, wherein,

Figure 1 is a perspective view of my grave cover.

Figure 2 is a cross sectional view on the line 2—2 of Figure 1.

Figure 3 is an end view of the cover.

There is illustrated a grave cover 10, consisting of two sections 11 and 12. The sections are illustrated as being of semi-circular formation, the section 11 being formed on a radius less than the section 12, so that the former section may be snugly nested within the latter, as clearly illustrated in the drawing. While the sections are illustrated and described as semi-circular in formation, this is not essential to the invention, since obviously, the sections may be formed in any approved shape, such a triangular, semi-elliptical, or otherwise.

The sections 11 and 12 may be stamped from any suitable gauge of sheet metal, galvanized or otherwise, each section including an end wall 13.

Each section 11 and 12 has a pair of leg members 14, downwardly extended from respective horizontal flanges 15 of respective sections. The legs 14 are of a length to be forced into the ground adjacent the boundaries of a grave for firmly securing the cover in position thereover.

As may be clearly seen in Figures 1 and 2, when the sections 11 and 12 are in nested position, the flanges 15 of the section 12 rest upon the flanges 15 of the section 11 and obviously, the sections may be longitudinally moved with respect to one another in order to accommodate graves of different lengths.

In order to reinforce the sections 11 and 12 against lateral spreading and to maintain adjustment of the sections, a tie plate or brace 16 is employed, having hook ends 17 adapted to engage over the lapped flanges 15 of the sections.

As shown in Figures 1 and 3, an end 13 of the cover is provided with an open loop 18, horizontally positioned to receive a marker stake 19, the latter being suitably driven in the ground for retention.

From the foregoing, it will be seen that I have provided a grave cover of extreme simplicity yet 20 of sturdy construction and affording a grave complete protection from weed growths as well as the weather, and while I have specifically described my construction, this is by way of illustration only, and I consider as my own all such modifications in structure as fairly fall within the scope 25 of the appended claim.

I claim:

A grave cover comprising a pair of hollow sections, each section having an outward laterally extended flange at its base and an end wall, one of the sections having a radius less than the other section and arranged to be nested therewithin and to bring the flanges into superposed abutting relation, a leg on the outermost corners of each flange, of a length to penetrate the ground for retention of the sections in nested relation and a brace plate extended transversely of the sections, said plate having hooked ends adapted to engage over and lie parallel with the overlapped flanges.

PURVIS T. HAMM.
